UNITED STATES PATENT OFFICE.

WILLIAM S. FANDREI, OF ASHTABULA, OHIO.

FURNACE.

Application filed December 22, 1924. Serial No. 757,446.

To all whom it may concern:

Be it known that I, WILLIAM S. FANDREI, a citizen of the United States, residing at Ashtabula, in the county of Ashtabula and State of Ohio, have invented certain new and useful Improvements in Furnaces, of which the following is a specification.

This invention relates to furnaces, more particularly to furnaces associated with steam generators, and has for one of its objects to provide a simply constructed device adapted to be located between the combustion chamber and smoke flue and operative to deflect and retard the products of combustion and produce an increased length of travel and longer path for the flames and ignitable gases, to increase the economy in the consumption of the fuel.

Another object of this invention is to provide a device of this character whereby the flames, as they pass beneath the attachment are caused to take a downward and spreading course thereby materially increasing the distribution chamber, and correspondingly increasing their efficiency and heat radiating properties, and whereby a larger percentage of the heat units are utilized, and prevented from passing out through the smoke flue.

Another object of the invention is to provide a device of this character including a rear wall of fire resisting units having a semi-conical upwardly and forwardly directed extension of fire resisting units and merging at the smaller end into the wall and spaced at its sides from the sides of the smoke area of a furnace.

With these and other objects in view the invention consists in certain novel features of construction as hereinafter shown and described and then specifically pointed out in the claim, and in the drawings, illustrative of the preferred embodiment of the invention—

Figure 1 is a longitudinal section of a portion of a conventional furnace and smoke flue, with the improved attachment arranged therein, the upper half of the attachment being in plan view and the lower half in longitudinal section.

Figure 2 is a section on the line 2—2 of Figure 1.

Figure 3 is a transverse section on the line 3—3 of Figure 2, looking in the direction of the arrow.

Figure 4 is a vertical section on the line

4—4 of Figure 2, looking in the direction of the arrow.

The improved device may be adapted without material structural change to furnaces of various constructions, but for the purpose of illustration is shown installed in a conventional furnace between the combustion chamber and smoke flue, the furnace wall being indicated at 10, the smoke flue at 11, a portion of the grate at 12 defining the combustion chamber at 13 and the ash pit at 14, with the bridge wall at 15.

Resting upon the grate bars 12 and against the main bridge wall 15 is an auxiliary or supplemental bridge wall represented as a whole at 16 and formed with a plurality of spaced transverse passages 17 and a longitudinally directed recess 18 with which the passages individually communicate at the upper side of the recess, as shown.

The rear side of the recess 18 is closed by the main bridge wall 15, and communicates at its lower side with the ash pit 14, through spaces between the rear or inner ends of the grate bars.

By this means a plurality of passages are provided between the ash pit and the combustion chamber, and supplying currents of air to the flames as they pass over the bridge wall, and materially increase the efficiency of the combustion.

Erected in the rear portion of the smoke arch, or at the lower portion of the smoke flue, is a supporting wall 19, and located at the juncture of the furnace shell 10 and the base of the smoke flue 11, is another supporting wall 20, the latter having a relatively large opening for the passage of the products of the combustion, as indicated in Figures 1 and 3, and springing from the supporting walls 19 and 20 is a deflector portion semi-conical in form and represented as a whole at 21. The members 19, 20 and 21 are constructed of a plurality of fire proof units or bricks, as shown, and the portion 21 by its arching and semi-conical form is self supporting on the supporting walls, the center or key of the arched portion being further supported by a post device 22, also of fire proof units.

The wall 19 and the semi-conical deflector portion 21 being formed of fire resisting units, and the portion 21 merging into the wall 19 without abrupt changes of direction of the inner faces, no ledges or projections

are produced to retard the course of the currents of the flames or the air or to provide lodgments for dust, ashes, or the like.

By this arrangement all of the products of the combustion are caused to pass through the opening in the wall 20 and beneath the deflector portion 21, and are directed downwardly thereby and divided and pass thence beneath the lower edges of the deflector and upwardly between the deflector and the side walls of the smoke flue, as indicated by the arrows.

The products of the combustion are thus retarded and caused to take a longer path in passing from the grate to the outlet flue, or other words the flames by contacting with the arched and semi-conical deflector, are turned downwardly thereby and caused to traverse a materially increased distance, whereby the ignitable gases are more thoroughly consumed and the smoke and other combustible particles also more thoroughly consumed by the coaction of the air passing through the supplemental bridge wall. The inverted arch portion also imparts a spreading action to the flames thereby causing a more equal distribution of the combustible gases, so that a much larger percentage of the heat units are utilized and prevented from passing out with the smoke.

The more complete combustion of the gases and more solid particles of the products of the combustion, materially decreases the deposit of soot and the like, as will be obvious.

By the action of the deflector cleaner tubes

and heating surfaces results, and the corresponding increase of efficiency and with less deposits in the ash pit.

The improved device is simple in construction and can be readily adapted to furnaces and generators of various sizes and construction.

The preferred embodiment of the invention is disclosed in the drawings and set forth in the specification but it will be understood that modifications within the scope of the claimed invention may be made in the construction without departing from the principle of the invention or sacrificing any of its advantages.

Having thus described the invention what is claimed is:

In a furnace including grate bars having a solid bridge wall extending across the rear ends thereof, a supplemental solid bridge wall resting upon said bars and extending transversely thereof against the face of said first mentioned bridge wall, said supplemental bridge wall having a recess in, and extending throughout the length of the back, said recess being of less height than the wall and opening through the grate therebeneath, and said supplemental wall further having a series of transverse passages therethrough opening at one end through the front of the wall and at the other end into the upper part of said recess.

In testimony whereof, I affix my signature hereto.

WILLIAM S. FANDREI.
